(57) **CLAIM**

The ornamental design for a valve element as shown and described.

DESCRIPTION

FIG. 1 is a perspective view of the top surface of the valve element embodying the invention.

FIG. 2 is a perspective view of the bottom surface of the valve element of FIG. 1.

FIG. 3 is a top view of the valve element of FIG. 1.

FIG. 4 is a bottom view of the valve element of FIG. 1.

FIG. 5 is a side view of the valve element of FIG. 1.

FIG. 6 is a further side view of the valve element of FIG. 1.

FIG. 7 is a perspective view of the top surface of the valve element in a further embodiment.

FIG. 8 is a perspective view of the bottom surface of the valve element of FIG. 7.

FIG. 9 is a top view of the valve element of FIG. 7.

FIG. 10 is a bottom view of the valve element of FIG. 7.

FIG. 11 is a first side view of the valve element of FIG. 7.

FIG. 12 is a second side view of the valve element of FIG. 7.

FIG. 13 is a third side view of the valve element of FIG. 7; and,

FIG. 14 is a fourth side view of the valve element of FIG. 7.

The elements shown in broken lines are included for the purpose of illustrating environment and form no part of the claimed design.
